UNITED STATES PATENT OFFICE.

EDWIN M. LEE, OF FARGO, NORTH DAKOTA, ASSIGNOR OF ONE-HALF TO GEORGE O. RICHARDSON, OF FARGO, NORTH DAKOTA.

STAND.

Application filed March 18, 1927. Serial No. 176,501.

This invention relates to a device for supporting a Christmas tree, or other element, in upright position.

Objects of the invention are to provide a very simple inexpensive construction; to provide a construction in which the elements can be quickly connected or disconnected; and to provide a device adapted to be operated as the result of a gravity action of the element 10 to be supported.

Features of the invention include the general arrangement, as well as all details of construction.

Objects, advantages and features will be 15 pointed out in the description of the drawings forming a part of this application, and in said drawings.

Figure 1 is a side elevation showing the device holding an element in upright position;

Figure 2 is a plan section;

Figure 3 is a plan section substantially on line 3—3 of Figure 1; and

Figures 4 and 5 are views illustrating the 25 manner of disconnecting a leg from its link.

The device comprises links 1 identical in construction and each having a closed loop 3 and a partially open loop 4, these loops being in this instance terminal, and lying in 30 the same plane. It is conceivable that the loops 3 may also be partially open to facilitate assembly. These links are arranged so that each loop is traversed by a link, thus providing a device comprising links slidably 35 connected together to form, what will be termed a running noose, or opening, which can be made, expanded or constricted as desired by sliding the links one upon the other. This opening or noose is adapted to be traversed by the element to be supported, in 40 this instance represented as a cylindrical rod or bar 5, which may be the bottom of a tree.

To each link is pivotally attached a leg 7, 45 and the attachment is pivotal. The connection is also slidable so that the leg can be disconnected from its link by simple swinging motions, in this instance in plane substantially at right angles to one another, one 50 in the plane of the loop 4. It is for this purpose that the loops 4 are partially open as at 8, see Figures 4 and 5. Each leg has two openings respectively designated 10 and 11, through which the loop is adapted to 55 pass. As shown in Figure 1 at the left each

leg is thus loosely traversed by the loop at two points whereby the swinging movements of the leg and link above mentioned can be made to instantly disconnect the parts. This disconnection is made in a manner shown in 60 Figures 4 and 5 first by swinging the leg in the plane of the loop, in a direction shown at A in Figure 4 and then further swinging the leg, about the opening 11 as a pivot, to a position substantially at right angles to 65 that shown in Figure 4, to have it assume the radial position shown in Figure 5, after which the leg is moved generally in the direction of the arrow B to disengage the opening 11 from the loop. 70

Each leg is provided with prongs 15 or equivalent devices whereby the legs can be made to positively engage the supported element. Thus when the upper ends of the legs are positively engaged as by driving the 75 prongs into the wood, and when the lower ends 16 are resting on the ground the weight of the tree tends to spread the legs in a direction of the arrow C, Figure 1, which results in pulling the rods in the direction of the arrow D which results in a constriction of the running noose so that the links which form the noose embrace the support as the result of gravity action of the support. The ends 16 are 80 curved substantially as shown to facilitate the sliding out action which results in the entrainment of the elements 1. 85

The device is simple and inexpensive and is at present constructed wholly from wire 90 and sheet material.

Figure 5 in addition to illustrating the manner of disconnecting the links and levers, also shows a modification in which the eye 3 is open as at 20. It will be understood that each element would be open at 20 so that one element could simply be hooked over another. Although it is evident that the links can be assembled by threading the loops 3 over the open ends of the loops 4, 95 yet this must be accomplished in such manner that the open portion 8 of the loop 4 faces downwardly, see Figure 1. In the modification of Figure 5, the open portions 8 and 20 lie on the same side so that when 100 an element 1 is pressed over another element and hooked there onto, the gap 8 will naturally be facing downwardly. 105

I claim as my invention:

1. A device of the class described compris- 110

ing links slidably connected to provide an opening to receive the element to be supported and legs one for each link pivotally connected thereto and having ends to frictionally engage the element above the opening the arrangement being such that the weight of the supported element acts to cause the links to embrace the element, each link having a partially closed terminal loop, and each leg being loosely traversed by the loop at two points, whereby by swinging movements the leg and link can be instantly disconnected.

2. A device of the class described comprising links slidably connected together to form a running noose to be traversed by the element to be supported, each link having a partially closed terminal loop and a leg for each link loosely traversed by the loop at two points, whereby simple swinging motions in two planes substantially at right angles to each other allow instant disconnection of the legs from the links.

3. In combination with a supported element, links slidably connected together to form a running noose about the element, a leg pivoted to each link and engaging the supported element as a fulcrum above the

noose, the opposite end of the legs being engaged with the floor, and the weight of the supported element acting to spread the legs and tighten the noose about the element.

4. A device of the class described comprising three wire elements each having a terminal loop traversed by one of the elements to form a running noose of substantially triangular configuration, a leg pivoted to each wire element at a point outwardly beyond the noose, and each leg having means engageable with an article to be supported which article is circumscribed by the loop, and to engage such article at a point above the loop, and each leg further having a portion below the point of attachment with the wire element, and the legs being arrangeable in pyramidal form, such that when the upper ends of the elements are engaged with the article to be supported the weight of the article acting upon the upper ends of these elements spreads their lower end, and causes the noose to be tightly drawn about the supported article.

In witness whereof, I have hereunto set my hand this 8th day of March, 1927.

EDWIN M. LEE.
